JINGLE STICK

Michael J. Valente, 116 Harding Terrace,
Dedham, Mass. 02026

Filed Jan. 9, 1967, Ser. No. 5,341
Term of patent 14 years

(Cl. D56—1)

FIG. 1 is a view in perspective of a jingle stick showing my new design,

FIG. 2 is a top plan view thereof,

FIG. 3 is an end view taken from the right-hand end of FIG. 2, and,

FIG. 4 is an end view taken from the left-hand end of FIG. 2.

The characteristic feature of my new design resides in the combination of the specifically configured openings in the stick and the particular arrangement of the jingles mounted therein.

I claim:

The ornamental design for a jingle stick, as shown and described.
